METHOD OF AIR CONDITIONING

Henry O. Forrest, Teaneck, N. J.

Application August 19, 1931, Serial No. 557,959

2 Claims. (Cl. 261—11)

This invention relates to air conditioning, and relates more particularly to a process for the conditioning of air for rooms, residences and other buildings, with respect to its dry bulb temperature and relative humidity for the purpose of alleviating physical discomfort caused by excessive dry bulb temperature or excessive humidity, or both.

According to this invention, I first dehumidify the air to a relative humidity lower than that necessary for comfort, preferably by the use of a liquid dehumidifying or dehydrating agent, and then cool the air by rehumidifying it to a higher relative humidity (but within the comfort range) by the use of an open spray of water. The dehumidifying step is preferably carried out without increase in the temperature of the air being conditioned, and may advantageously be conducted substantially isothermally so far as the air temperature is concerned. In order to accomplish this and at the same time permit protracted use of the dehydrating agent, it is necessary to remove the heat of absorption from the dehydrating agent by suitable cooling means during its use in the dehumidifying step.

The step of cooling the air by humidifying it with a water spray is preferably accomplished substantially adiabatically, since available cooling water is ordinarily at a temperature above that of the wet bulb temperature of the air being humidified and only by adiabatic evaporation can the cooling water be reduced to the desired wet bulb temperature and used repeatedly. Of course, if the available cooling water were below the wet bulb temperature, and its repeated use were not deemed desirable, the cooling and humidification step could be effected without resorting to adiabatic evaporation.

By the combined steps of dehumidification and humidification as described above, I avoid the necessity of refrigerating the air or the cooling water by special refrigeration apparatus. So far as I am aware, all prior systems of air conditioning, which accomplish comparable results, have involved cooling by such use of refrigerating apparatus, which is usually quite complicated and expensive in character.

The dehydrating agent must of course be susceptible to simple and inexpensive activation or regeneration. For practical reasons, it is desirable that it be such as to be capable of being regenerated simply by driving off the absorbed water by heating. Although solid dehydrating agents or absorbents of this character are known and may be employed in my process, I prefer

to use liquid dehydrating agents as they lend themselves readily to the development of inexpensive and compact apparatus capable of being operated either continuously or intermittently as desired.

One of the primary objects of this invention is to accomplish the conditioning of air with respect to its temperature and humidity without the use of refrigeration in the accepted sense of the term.

Another object of this invention is to dehumidify air by the use of liquid dehydrating agents.

Other objects and advantages of this invention will be apparent from the following description, taken in conjunction with the accompanying drawing, in which:

The figure is a schematic layout of an apparatus adapted for continuously conditioning air in accordance with my novel method.

Referring more particularly to the drawing, the space to be conditioned is diagrammatically represented at 10, and is provided with an outlet register 11 and an inlet register 12 connected respectively to an outlet air duct 13 and inlet air duct 14. It will be understood that where the space to be conditioned is an entire building, there will be a plurality of inlet and outlet registers which may connect into a common outlet duct 13 and a common inlet duct 14, respectively. The outlet register will ordinarily be located near the top of the space to be conditioned and the inlet register near the bottom, as shown in the drawing, although this arrangement is not essential and may be varied if desired.

Air to be conditioned is withdrawn from the space 10 through the outlet duct 13 by the air pump 15, and discharged into a dehumidifier 16. The dehumidifier 16 is shown as divided into four sections 17 by spaced baffles 18. The air to be dehumidified flows through the dehumidifier 16 from an inlet 19, into which a pump 15 discharges, to an outlet 20, passing through each of the baffles 18 in turn. The bottoms of the baffles 18 are imperforate and constitute dams of increasing height from the air inlet end to the air outlet end of the dehumidifier. The liquid dehydrating agent, which may be, for example, a concentrated solution of calcium chloride brine, may be introduced into the last or air outlet section 17 of the dehumidifier 16 near the bottom thereof through the pipe 21, and forms a pool 22 of liquid dehydrating agent in said last section 17. The dehydrating agent overflows from the pool 22 into a pool 23 in the next section 17, thence into a pool 24 in the succeeding section and finally into the

bottom 25 of the first or air inlet section 17. It will be understood that the height of each pool is determined by the height of the imperforate lower portion of the baffles 18.

- 5 Separate pumps 5, which may if desired be driven by a common prime mover 26, pick up the liquid dehydrating agent from the bottom of each section 17 and introduce the same into the top of the same section through spray nozzles 27.
- 10 Obviously a plurality of spray nozzles may be used in each section.

The liquid dehydrating agent in passing downwardly in the form of a fine spray through the air passing through the dehumidifier, absorbs 15 moisture from the same and consequently reduces the absolute humidity of the air being conditioned. By virtue of the location of the air inlet and the arrangement of chambers 17 and pools 22, 23, 24 and 25, the dehydrating agent 20 when at a point of highest concentration contacts air in a zone of least moisture content so that increased efficiency of dehydration is effected by what is substantially a counterflow arrangement of air and dehydrating agent.

- 25 A part of the dehydrating agent circulated by the pump 5 connected to the first section 17 is diverted through a pipe 28 to a heat exchanger 29 and thence to an evaporator 30. The part of the dehydrating agent diverted and regenerated 30. may be concentrated to a higher degree than necessary for effecting absorption and this regenerated agent when mixed with that portion of the dehydrating fluid already circulated through the spray will bring the entire body of the dehydrating fluid to the desired degree of concentration.

The evaporator 30 is heated by a heating element indicated diagrammatically at 31, and may be of any suitable construction adapted to heat 40 the dehydrating agent to expel the absorbed water therefrom such as a gas burner, an electric heater or a steam coil. The water thus removed from the dehydrating agent is discharged to the outside air through a pipe 32 in the form of steam or water vapor. The regenerated dehydrating agent which is at high temperature is picked up by a pump 33, forced through the heat exchanger 29 countercurrent to the dehydrating agent about to be regenerated transferring most of its sensible heat thereto, and thence 45 is delivered to a suitable cooler 34. In the cooler 34 the regenerated dehydrating agent is cooled by indirect heat exchange with either cooling water or outside air or other cooling agent, as desired, to a temperature approximating that of the air to be conditioned, and is then discharged through a pipe 21 to the dehumidifier 16 as described above.

The dehumidified air is discharged from the dehumidifier 16 through the outlet 20 and introduced into a humidifier chamber 40. Water is sprayed into the top of the humidifier 40 through the spray nozzle 41, and is recirculated from the bottom of the chamber 40 back to the nozzle 41 by means of a pump 42. Additional water to 60 compensate for that removed by evaporation in the chamber 40 may be supplied from time to time as required from any suitable source, such as a supply pipe 43. Since the water used in the chamber 40 is recirculated continuously and only a small percentage of the total water in circulation is evaporated, the water rapidly assumes the wet bulb temperature of the air. The system is 65 preferably insulated so that there is little heat interchange with the surrounding atmosphere.

Under these conditions, adiabatic evaporation of the water into the air takes place, the sensible heat necessary for this evaporation being taken from the air and reducing its dry bulb temperature while increasing its relative humidity. Obviously, the fractional humidifications thus obtained must be so controlled that the final relative humidity of the air is within the comfort range for air of the temperature in question. The air so conditioned is then returned to the space 10 10 through the inlet duct 14.

In order to remove the heat produced by the absorption of the water in the dehydrating agent in the dehumidifier 16, water is continuously circulated through closed cooling coils 50 immersed 15 in the pools 22, 23 and 24 in the bottom of the dehumidifier by a pump 51 and suitable inlet pipes 52. After passing through the coils 50, the cooling water is conducted through a pipe 53 to the top of a water cooling tower 55 of conventional construction, from the bottom of which the pump 51 takes its suction. In the water cooling tower 55, the cooling water is reduced in temperature by evaporation in contact with the outside air in the well known manner. If 25 desired, the cooler 34 may be connected in circuit with the pump 51 and tower 55 as shown. An air outlet 57 with a blower 58 may be associated with the tower 55 to improve air circulation in the tower and aid in the removal of heat.

Where city water or other plentiful source of cooling water of sufficiently low temperature is available, the cooling tower 55 may be omitted, and the cooling water run to waste after passing through the cooling coils 50.

In order to supply fresh air for ventilation, outside air may be admitted to the inlet of the pump 15 through a conduit 54 as required.

As an example of the carrying out of my invention, the following figures are given, simply 40 by way of illustration. Let us assume that the air discharged from the pump 15 is at a temperature of 85° F. and has a relative humidity of 47%. This air, of course, comprises an admixture of the air withdrawn from the space 10 to 45 be conditioned and the fresh air (say 20%) for ventilating purposes admitted from the outside. Let us assume further that the dehydrating agent is a 48% solution of calcium chloride brine and is introduced into the dehumidifier 16 at this 50 same temperature of 85° F. and is maintained at that temperature by the cooling water circulated through the cooling coils 50. It will be apparent that under these conditions the air leaving the dehumidifier will still be at a temperature of 85° F. but that its relative humidity will be reduced. The amount of reduction of the relative humidity will, of course, depend upon the rate of circulation of the dehydrating agent and its water absorbing properties, but it is perfectly 60 practicable under the conditions stated, to reduce the relative humidity to 30%. The air entering the humidifier 40 will therefore be at a temperature of 85° F. and have a relative humidity of 30%. By proper design of the humidifier 65 40, it is readily possible to secure a cooling of the air of 10° F. by adiabatic evaporation. Under such conditions, we may determine from the standard humidity chart that the air leaving the humidifier 40 will have a relative humidity 70 of 54%. Air at a temperature of 75° F. and a relative humidity of 54% will result in a somewhat higher temperature and lower relative humidity in the conditional area 10, which would be found very comfortable, both to people stay- 75

ing in the space 10 for long periods and to those only passing through or present for short periods of time, in comparison with outside atmospheric conditions of say 85° F. and 75% relative humidity which would produce the entering mixture at the pump 15 referred to.

Instead of using calcium chloride brine as a dehydrating agent, other hygroscopic substances having a strong affinity for water may be employed, for example, a caustic soda solution, 10 glycerine or triethanol amine.

It is further contemplated as a part of this invention that some purifying agent such as a weak solution of calcium hydroxide may be substituted for water in the humidifier 40. In case 15 such an agent were used, in addition to the humidifying action taking place as described in connection with the humidifier, an appreciable amount of carbon dioxide would be removed from 20 the air resulting in its purification. The precipitated calcium carbonate resulting from such an action could be removed in any manner desired as by setting, and more calcium hydroxide could be added to the system as needed.

25 The dehumidifying apparatus used for carrying my novel method into practice has been described as delivering the dehydrated air to the humidifier at the same temperatures at which it was received. Obviously, however, by controlling 30 the quantity or the temperature of the cooling water circulating through the coils 50 or by controlling the temperature of the water or purifying medium utilized in the humidifier, temperature control of the air may be effective in either place desired either by simultaneous regulation or independently of each other.

Although my novel method is especially advantageous when it is desired to impart desired characteristics of temperature and humidity to air by utilizing a step that involves cooling the air, it is obvious that by circulating a heating 5 medium through the coils 50 by spraying the dehydrated air with a hot fluid or vapor in the humidifier, or by spraying the air by a heated fluid of proper hydration characteristics in the dehumidifier that cold air may be heated to a 10 desired temperature within the healthful comfort range while being given desired characteristics of humidity so that the novel method may be used when it is desired to condition air in winter as well as in the summer time. 15

I claim:

1. A method of conditioning air which includes the steps of contacting said air with a circulated hygroscopic liquid of controlled concentration and dehydrating said air to a high degree while 20 continuously removing heat of absorption from said hygroscopic liquid, and contacting said air with a spray of water and imparting thereto conditions of temperature and humidity to place it within the comfort range. 25

2. A method of conditioning air which includes the steps of progressively subjecting said air to the action of a circulated hygroscopic liquid in zones of varying concentration of said liquid, removing heat of absorption from said liquid between points of contact in said zones, withdrawing a portion of said liquid from a zone of lesser concentration, regenerating said withdrawn portion, and returning said regenerated liquid to a zone of greater concentration. 30 35
